UNIVERSAL MOUNTING

Harold W. Evans, Wilkes-Barre, Pa.

Application October 18, 1937, Serial No. 169,615

1 Claim. (CL. 89—37)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a universal mounting. The purpose of the invention is to provide a simple and easily constructed universal mounting which is adapted to carry a member to be pointed, which may be readily and quickly assembled, which will effectively shield the interior, and which will afford ample movement for the member to be pointed.

5 The invention is characterized by the employment of a large and a small cylinder, the small cylinder being mounted in the large cylinder on an axis perpendicular to the axis of the large cylinder and remote therefrom.

To these and other ends, the invention consists in the construction, arrangement and combination of elements described hereinafter and pointed out in the claim forming a part of this specification.

A practical embodiment of the invention is illustrated in the accompanying drawing, wherein:

5 Fig. 1 is a longitudinal sectional view of a mounting constructed in accordance with the invention.

Fig. 2 is a view in front elevation.

30 Fig. 3 is a sectional view on the line 3—3 of Fig. 1.

There is shown a portion of an armored wall 5 which is provided with a rectangular opening 6 for receiving a relatively large hollow cylinder 7 constituting a shield and having its axis disposed horizontally and substantially in the plane of the opening. The parallel sides of the cylinder are provided with aligned trunnions 8—8 which are axial of the cylinder and are mounted in bearings 9—9 fixed to the inside of the wall 5 on opposite sides of the opening 6.

The rear portion of the cylinder which is disposed on the inner side of the wall 5 is cut away as shown at 10 (Fig. 1), so that access may be had to the interior of the cylinder. The front or outer portion of the cylinder is preferably formed with a flat face 11 which is provided with a rectangular opening 12.

A relatively small hollow cylinder 13 constituting a cradle is disposed in the opening 12 with its axis arranged vertically and substantially in the plane of the opening 12. The parallel top

and bottom ends of the cylinder are provided with aligned trunnions 14—14 which are mounted in bearings 15—15 fixed to the inside of the flat face 11 on opposite sides of the opening 12.

The rear portion of the cylinder 13 is cut away 5 as indicated at 16 to give access to its interior. The front or outer portion of this cylinder is provided with an opening 17 and a projecting annular lip 18. The cylinder 13 includes a rearwardly extending bracket 19 having spaced 10 aligned apertures 20—20 in its rear extremities. A pin 21 inserted in the apertures serves to attach an instrument to be pointed such as a gun 22 whose barrel or barrel jacket 23 passes through the opening 17 and is supported therein. The 15 cradle cylinder is provided with an opening 24 for accommodating an auxiliary instrument, such as a telescope.

In order to move the gun in traverse, it is only necessary to act horizontally on its breech end 20 and cause the cradle cylinder 13 to be rotated on its trunnions 14. In order to move the gun in elevation, the operator acts vertically on the gun, and the cradle cylinder 13 transmits this pressure to cause the shield cylinder 7 to rotate on 25 its trunnions 8. These movements may be combined and the gun can be freely pointed in any direction within the limits imposed by the structure.

I claim:

30 In a gun mounting, a relatively fixed support having a rectangular opening, a shield consisting of a hollow cylindrical wall with parallel side walls having trunnions axial of the cylinder, said shield disposed in the opening of the support 35 with the trunnions of the shield substantially in the plane of the opening, means on the support for mounting the trunnions of the shield, said cylindrical wall having a rectangular opening, a cradle consisting of a hollow cylindrical 40 wall with parallel top and bottom walls having trunnions axial of the cylinder, said cradle disposed in the opening of the shield, means on the shield for mounting the cradle trunnions adjacent the opening in the shield with the axis of 45 the cradle trunnions remote from the axis of the shield trunnions whereby the cradle trunnions are movable in an arc through the opening in the fixed support and are normally disposed forwardly of the support.

30

HAROLD W. EVANS.
